Ch. Farren
Attorney

Patented Nov. 25, 1924.

UNITED STATES PATENT OFFICE.

WILLIAM H. BOND, OF SARASOTA, FLORIDA.

HANDPIECE FOR DENTAL DRILLS.

Application filed October 29, 1923. Serial No. 671,511.

To all whom it may concern:

Be it known that I, WILLIAM H. BOND, a citizen of the United States, residing at Sarasota, in the county of Sarasota and 5 State of Florida, have invented certain new and useful Improvements in Handpieces for Dental Drills, of which the following is a specification.

This invention relates to dental drills, and 10 more particularly to improvements in the hand pieces of dental engines.

In the usual construction of dental engines, they are provided with hand pieces surrounding the drill shaft and adapted to 15 be grasped by the operator when using the drill.

An object of the present invention is to provide a two-part hand piece, one of which is formed as a sheath arranged over the 20 other and adapted to be removed for sterilizing.

More specifically, the invention consists of an inner sleeve surrounding the drill shaft and adapted to serve as a cover to hold 25 the oil or other lubricant used on the shaft, and an outer sleeve or sheath adapted to be grasped by the operator of the drill. This outer sleeve is readily removable and is adapted to be removed at intervals for the 30 purpose of sterilizing it. When the usual type of one part hand piece is employed, it is inexpedient to remove it for sterilizing, as it also serves as a retainer for the oil or other lubricant on the shaft and its removal 35 is, for this reason, inconvenient.

In the accompanying drawings, I have shown one embodiment of the invention. In this showing:

Figure 1 is a plan view,

Figure 2 is central longitudinal sectional view,

Figure 3 is a transverse sectional view on line 3—3 of Figure 2,

Figure 4 is a similar view on line 4—4 of Figure 2, and,

Figure 5 is a detail view of the hand piece.

Referring to the drawings, the reference numeral 1 designates a supporting bracket of the usual construction on which the drill 50 is mounted. This bracket is provided with a circular portion 2, one end of which is externally screw-threaded, as at 3. A hollow drill shaft 4 is supported in a bearing 5, carried by the bracket and the shaft passes 55 through the bracket and is provided with a

pulley 6 for the reception of a cable to rotate the shaft. The drill is provided with the usual chuck 7 to receive a drill bit and this chuck is controlled by means of a rod 8, passing through the shaft to the rear end 60 and having an operating handle 9 arranged thereon.

The device forming the subject matter of the present invention consists of a hand piece formed of an inner section 10 and an outer section 11. As shown, the inner section surrounds the drill shaft and serves as a container therefor. The bore of the inner section is provided with a slightly enlarged portion adjacent the rear end, forming a shoulder for the reception of the bearing 5 and is further provided with a flange 12, at its inner end adapted to abut the circular portion 2 of the supporting bracket. Adjacent the rear end, it is further provided with a raised portion 13, adapted to receive and support a spring member 14. The spring member is provided with a slight offset 15, intermediate its ends. The rear end of the spring is secured to the inner sleeve 80 by suitable fastening elements 16. A locking member 17, formed of metal or other suitable material, is secured to the spring member adjacent its forward end and this member is provided with a tooth 18. The rear end of the locking member is slightly spaced from the spring and, as shown, is provided with an elongated slot 19, through which access may be had to the fastening element 16. The inner sleeve is adapted to be secured over the drill shaft by means of a nut 20, having threads adapted to engage the threads 3 on the circular portion of the bracket. As shown in Figure 2 of the drawings, this nut contacts with the flange 95 12 on the rear of the sleeve. The nut is provided with a longitudinal slot 21 (see Figure 4) to permit it to be passed over the raised portion 13 of the sleeve.

The outer sleeve forms a sheath adapted 100 to fit over the inner sleeve and is removably secured thereto by means of the tooth 18. As shown, the outer sleeve is provided with a depression 22 in which the tooth is adapted to be received. It is also provided with a longitudinal slot 23, extending from the rear to permit the outer sleeve to pass over the raised portion 13. The forward end of the outer sleeve extends beyond the forward end 105 of the inner sleeve and is tapered, as at 24. 110

This forms a support for the bur or drill and also prevents saliva from collecting on the forward end of the inner sleeve.

The operation of the device will be apparent from the foregoing description. It is assembled by first placing the inner sleeve in position, then placing the nut 20 on the sleeve and then securing the retaining member 17 to the inner sleeve by inserting the fastening elements in the spring 14. The inner sleeve is placed in position by placing the slot 23 in alinement with the raised portion 13 and sliding it over the inner sleeve until the tooth 18 enters the notch 22. When the outer sleeve is to be removed, the rear end of the locking member 17 is depressed, raising the tooth 18 from the notch 22 and permitting the outer sleeve to be removed. This outer sleeve may be removed at any time for the purpose of sterilizing it, and the inner sleeve serves as a cover or retainer for the drill shaft when the outer sleeve has been removed.

It is to be understood that the form of the invention herewith shown and described is to be taken as a preferred example of the same, and that various changes in the shape, size, and arrangement of parts may be resorted to without departing from the spirit of the invention or the scope of the subjoined claims.

I claim:

1. In a dental engine, a hand piece comprising an inner sleeve, means for securing said sleeve in position, a sheath surrounding said sleeve, said sheath being provided with a notch, a leaf spring having one end secured to said sleeve, the other end of said

spring being offset, a locking member secured to the offset end of said spring, and a tooth formed on said locking member and adapted to enter said notch.

2. In a dental engine, a hand piece comprising an inner sleeve, means for securing said sleeve in position, a sheath surrounding said sleeve, said sheath being provided with a slot at its rear end, and being further provided with a notch spaced from said slot, and a resilient locking member arranged on the exterior of said sleeve, said locking member being adapted to enter said slot and being provided with a tooth adapted to be received in said notch.

3. In a dental engine, a hand piece comprising an inner sleeve, means for securing said sleeve in position, a sheath surrounding said sleeve, a resilient catch carried by said inner sleeve and adapted to engage said sheath to detachably secure it in position against longitudinal movement, and means engaging said sheath for preventing rotation thereof.

4. In a dental engine, a hand piece comprising an inner sleeve, means for securing said sleeve in position, said sleeve being provided with a longitudinal raised portion, a sheath surrounding said sleeve and provided with a longitudinal slot to receive said raised portion, said sheath being further provided with a notch in alinement with said slot, and a locking member carried by said raised portion and adapted to enter said notch.

In testimony whereof, I affix my signature.

WILLIAM H. BOND.
